ORNAMENTAL MOLDED FIGURE

Henry P. C. Keuls, New York, N. Y.

Application February 18, 1936, Serial No. 64,500

2 Claims.

(CL 215—12)

This invention relates to ornamental molded figures hollowed-out to receive a bottle or other similar container, particularly for beverages.

In many instances, it is desirable to have liquid refreshments on display or handy for serving, but as the commercial bottles or containers in which they are sold are rather unsightly, the custom is usually followed of transferring the beverage to some other container more ornamental in design. This inconvenience, coupled with the fact that the identity of the brand may be forgotten, makes the practice not quite as satisfactory as it might be. Then, too, in the case of alcoholic beverages, it is quite illegal to transfer the beverage from one bottle to another. The law requires that the beverage be dispensed from its original container.

In accordance with the present invention, an ornamental molded figure is provided which can be attractively displayed, and which is hollowed-out to receive the commercial container in which the beverage is sold and with the label in its original condition. While not in use the container is thus completely hidden from view, whereas when the beverage is served the knowledge of its particular brand is at once available. In addition the inconvenience of transferring the beverage from one container to another is obviated.

The design of the molded figure is, in most cases, dictated by the shape of the hollowed-out portion in order that the walls of the ornamental figure may be made substantially uniform in thickness, thus rendering the article light in weight and economical to manufacture. Above the base, the figure is formed in two parts, in the present embodiment the split occurring in a horizontal plane substantially at the center of the figure, so that the upper portion thereof may be separated from the lower portion to give access to the interior for the removal and replacement of the bottle. The lower portion which is hollowed-out to receive the larger body portion of the bottle, if desired, may be equipped with resilient means capable of conforming to bottles of different sizes and shapes, and which serve also to align the upper portion or neck of the bottle with the upper smaller hollowed-out portion of the figure.

Referring to the drawings:

Fig. 1 is a face view of an ornamental figure embodying the present invention;

Fig. 2 is a side view of the ornamental figure shown in Fig. 1;

Fig. 3 is a sectional view on line 3—3 of Fig. 1;

Fig. 4 is a side view of the ornamental figure

shown in Fig. 1, with the upper portion removed to expose the bottle; and

Fig. 5 is a transverse sectional view taken on line 5—5 of Fig. 3.

In the embodiment of the invention illustrated, there is provided an ornamental figure molded in two parts A and B, the lower part A being hollowed-out to receive the larger or body portion of a bottle C and formed integral with a base portion A¹ on which the bottle rests when in the ornamental figure. The upper portion B of the figure likewise is hollowed-out to receive the bottle neck and for this reason the dimensions of the upper hollowed-out portion are substantially smaller than those of the lower portion.

In the lower hollowed-out portion A of the figure, there are provided longitudinal leaf springs a fastened at their upper ends, as by spot-welding, to a ring a¹ fitted and secured to the inner wall of the lower portion A of the figure. The ring a¹ extends above the edge of the portion A and fits within the upper portion B of the figure when the latter is in place. The leaf springs a, at their lower ends, are bent inwardly beneath a circular plate a² which is arranged in slight spaced relation with the base of the figure to give a degree of movement sufficient to provide for the flexing of the springs as the bottle is inserted in place. This arrangement not only holds the bottle firmly in place and aligns the neck portion centrally with the upper smaller hollowed-out portion, but in addition serves as a shock absorber to prevent breakage of the bottle when the latter is inserted in place.

It is desirable that the walls of the figure be molded to substantially the same thickness throughout in order to save material and to make the figure as light as possible. It will be seen therefore, that the shape of the interior hollowed-out portion of the figure at once dictates the character of the exterior design and, by way of illustration, a Janus-faced statuette of a man has been depicted, the trunk portion of which will house the large body portion of the bottle, and the head portion the neck of the bottle. The smaller head portion of the figure also permits it to be readily grasped so that the upper portion of the figure can be removed, exposing the neck of the bottle by which the same may be readily removed from and replaced in the lower portion of the figure.

Since, in the present embodiment, the upper portion B is entirely removable from the lower portion A, means in the nature of a dowel pin a³ has been provided on the upper edge of the low-

er portion of the figure and which is adapted to cooperate with a corresponding recess *b* formed in the lower edge of the upper portion of the figure, to insure that the parts are properly located when fitted together to maintain the continuity of design.

The design of the ornament is further selected with the idea of providing some portion thereof that will efface or render difficult of discernment, 10 the place where the parts fit together, and in the present instance it will be noted that the belt *B*¹ of the figure effectively accomplishes this purpose, the lower edge of the belt, which protrudes beyond the outer surface of the trunk, being in 15 alinement with the place where the parts come together.

From the foregoing it will be apparent that the invention satisfies a need long felt for a device that will hide a beverage bottle while having it always available, and which at the same 20 time serves as a handsome ornament for purposes of display.

In the accompanying drawings, the invention has been shown merely by way of example and 25 in preferred form, and obviously, many variations and modifications may be made therein which will still be comprised within its spirit. It is to be understood therefore, that the invention is not limited to any specific form or embodiment, 30 except insofar as such limitations are specified in the appended claims.

Having thus described my invention, what I claim is:

1. An article of manufacture, comprising a low-

er integral portion hollowed-out to receive the body portion of a bottle, an upper integral portion arranged to fit on the lower portion and hollowed-out to receive the upper or neck portion of the bottle, said portions when fitted together completely hiding the bottle from view, means extending beyond the edge of one of the portions and fitting within the other portion for holding said portions against lateral displacement and including a cylindrical element secured to the 10 inner wall of the lower portion, and means for holding the bottle in place in said lower portion, said means including a plurality of longitudinal inwardly bowed leaf springs fastened at their upper ends to said cylindrical element and adapted 15 resiliently to engage the lower body portion of the bottle so as securely to hold it in place.

2. An article of manufacture, comprising a lower integral portion hollowed-out to receive the body portion of a bottle, an upper integral portion arranged to fit on the lower portion and hollowed-out to receive the upper or neck portion of the bottle, said portions when fitted together completely hiding the bottle from view, a ring 20 arranged at the top of said lower portion projecting above the upper edge thereof, and adapted to fit into the upper portion, and means for holding the bottle in place in said lower portion, said means including a plurality of longitudinal inwardly bowed leaf springs fastened at their upper ends to said ring and adapted resiliently to 25 engage the lower body portion of the bottle so as securely to hold it in place.

HENRY P. C. KEULS.
